MOTION TRANSMITTING MECHANISM

John Q. Holmes, Linden, N. J., and Calmer E. Gordon, deceased, late of Markleville, Ind., by Nellie M. Gordon, widow and legal representative, Emporia, Ind.; said Holmes and said Calmer E. Gordon assignors to General Motors Corporation, Detroit, Mich., a corporation of Delaware

Original application July 8, 1941, Serial No. 401,544. Divided and this application March 11, 1943, Serial No. 478,770

5 Claims. (Cl. 74—426)

This invention relates to hydraulic presses having rotary plate conveyors carrying a plurality of work holders which are automatically moved into position to be operated upon by the ram of the press. This application is a division of Ser. No. 401,544, filed July 8, 1941. In that application, the object of the invention is to provide a self-contained hydraulic press unit of the enclosed type which can be adapted for various kinds of work and operations by the selection of suitable subassemblies of a number of interchangeable subassemblies. This object is accomplished by providing a table supported by a base which encloses a reservoir for containing a pressure fluid and a motor drive pressure pump unit mounted over the reservoir. The table supports a pedestal on one side of which is mounted a ram unit providing one or more rams operated by pistons operating in hydraulic cylinders. The table supports a rotary plate conveyor or dial feed which may be one selected from a number of interchangeable dial feed units. The pedestal, which supports the ram unit, provides an enclosure for a dial feed operating mechanism and for a cam operated valve for controlling the admission and the discharge of pressure fluid with respect to the ram cylinder in timed relation with respect to movements of the dial feed. The dial feed operating mechanism and the valve-controlling cam are operated by an electric motor contained within the housing provided by the pedestal.

The claimed subject matter of the present application is the dial feed unit comprising a turn table and its operating mechanism provided with a facile means for adjusting the timed relation between the dial feed operating mechanism and the valve controlling cam.

Further objects and advantages of the present invention will be apparent from the following description, reference being had to the accompanying drawings wherein a preferred embodiment of the present invention is clearly shown.

In the drawings:

Fig. 1 is a side elevation of an hydraulic press embodying the present invention.

Fig. 2 is a sectional view on line 2—2 of Fig. 3 and is drawn to a larger scale.

Fig. 3 is a composite view in the direction of arrow 3 of Fig. 1 and comprises segments AB, BC and CA. Segment AB is a plan view of the dial feed; BC is a sectional view on line BC of Fig. 4; and the segment CA is a sectional view on the line CA of Fig. 1.

Fig. 4 is a sectional view on line 4—4 of Fig. 3. The machine comprises a base 20 providing a

10 tank for containing a hydraulic pressure fluid. The base 20 supports a cover plate 25 providing a base for supporting certain elements of an hydraulic pressure system, including an electric motor driven fluid pressure pump whose connections with pipes 144 and 140 leading respectively to the upper and lower ends of cylinder 125 are controlled by a valve operated by a shaft 114a which is driven by the electric motor through a speed reducing gear.

The plate 25 supports a box-like frame 60 for enclosing the electric motor, pressure pump and control valve. Ventilation is provided for by one or more screened openings 63. The frame 15 60 supports a platform or table 70a which supports a casting 71 having a mounting pad 121 to which is secured a frame 122 providing a guide for a ram 123 and a support for an hydraulic cylinder 125 enclosing a piston (not shown) connected by part 128 with the ram 123. The mounting pad 121 is so shaped as to accommodate any one of a series of castings such as the casting 122. The ram 123 operates a tool unit 124a which causes an intermediate tool unit 260 20 to operate upon work carried by one of a plurality of work holders 125a mounted upon a dial feed turn table 161a.

The turn table 161a is part of a turn table unit which may be one of several units adapted to be mounted interchangeably on the platform 70a. The unit includes a housing 160a having a boss 163a holding a rod 164a which supports a tray 168a. Rod 164a provides a journal for supporting a bearing sleeve 165a fitted into turn table 161a which is supported vertically by a ball bearing 162a. The turn table 161a is caused to be intermittently rotated by a mechanism driven by the shaft 114a.

The mechanism for intermittently rotating the table 161a will now be described with reference to Figs. 2, 3 and 4. Housing 160a provides bearings at 184, 185 for shaft 114a which drives a gear 186 meshing with a gear 187 keyed to a shaft 188 (Fig. 3). Shaft 188 is journalled in bearings 189 and 190 provided by the housing 160a. The right hand portion of the shaft 188 is tubular and is externally threaded at 191 to receive a nut 192 which when tightened causes the following parts to be gripped between the nut 192 and a shoulder 188a of shaft 188, namely: the hub of gear 187, a spacing sleeve 193 and the inner race 194 of ball bearing 190. The shaft 188 supports and drives a cam unit 195 having a longitudinal spline connection with shaft 188 as indicated at 196. The cam unit 195 can be adjusted longitudinally along the shaft and locked in the de-

sired position of adjustment. For this purpose the central bore 188b of shaft 188 receives a rod 200 connected with the cam unit 195 by a cross pin 201 extending through longitudinal slots 202 provided by the shaft 188. Rod 200 is provided with a portion 203 of reduced diameter threaded to receive a nut 204. When the nut is tightened the following parts are clamped between the nut and a shoulder 205 of the rod 200, namely: an externally threaded sleeve 206 having a hex head 207 and a washer 208. When the nut 204 is slightly loosened, the threaded sleeve 206 may be turned. Since this sleeve is threadedly connected at 209 with the shaft 188, rotation of the sleeve 206 by applying a wrench to its head 207 will cause the rod 203 to move axially and relative to the shaft 188. This will cause the cam unit 195 to be moved longitudinally with respect to shaft 188. When the cam 195 has been located in the desired position of adjustment a nut 210 threaded on the sleeve 206 can be tightened down against the right end of shaft 188 and the nut 204 can be tightened against the washer 208 and the latter against the hex head against sleeve 206. In this way, the rod 203 is secured in the desired position of adjustment with respect to the shaft 188. The adjusting parts including the nut 192, the nut 210, the hex head 207 and the nut 204 are enclosed by a cup shaped housing 211 secured to the housing 160a by a plurality of screws 212.

The cam unit 195 is provided with a cam groove 220 for receiving cam follower rollers 221. Each roller 221 is mounted on a pin 222 attached to turntable 161a. The cam groove 220 is so shaped that the table 161a is moving during about one-half revolution of shaft 114a and shaft 188 and is stationary for about one-half revolution. The cam 195 is so related to the hydraulic-valve controlling cam that while the table 161a is stationary, the ram 123 moves downwardly to cause an operation to be performed on the work piece and then the ram returns to upward position. As the cam 195 is viewed in Fig. 3, it will be seen that one of the rollers 221a is entering the groove 220 while an adjacent roller 221b is moving from the groove, rotation of cam 195 being in the direction indicated by arrow 195a. By the time the roller 221a has arrived at the non-camming part of the groove indicated at 220a the table 161a will have been moved into such position that a work-holder 124a will have been brought into alignment with the tools controlled by the ram of the press or at least into such position that one of the pilot bushings 173a (Figs. 1, 3 and 4) is in alignment with the pilot rod 174a attached to the upper member of the tool unit. In order to make this alignment as perfect as possible the cam 195 is adjustable along the shaft 188 by the means which has been described with reference to Fig. 2.

The shaft 164a which provides a journal for the table 161a, also supports a tray 168a for containing articles which are to be assembled by the machine.

While the embodiment of the present invention as herein disclosed, constitutes a preferred form, it is to be understood that other forms might be adopted, all coming within the scope of the claims which follow.

What is claimed is as follows:

1. In a device of the character described, the combination of a rotary element, a plurality of

members connected with the element and equally spaced in a circular row, a cam for successively engaging said members, a shaft for driving the cam and having a central bore, and diametrically opposite longitudinal slots, a cross pin connected with the cam and extending across the bore and through the slots of the shaft, a rod within the bore attached to the cross pin, a sleeve surrounding the rod and threadedly connected with an end of the shaft, means limiting endwise movement of the rod relative to the sleeve whereby rotation of the sleeve causes the rod and the cam to move longitudinally of the shaft, and means for securing the sleeve against rotation from the desired position of adjustment.

5 2. In a device of the character described, the combination of a driven element, a rotary cam for driving said element, a shaft for driving the cam and having a central bore, and diametrically opposite longitudinal slots, a cross pin connected with the cam and extending across the bore and through the slots of the shaft, a rod within the bore attached to the cross pin; and means for securing the rod to the shaft in a desired position of longitudinal adjustment.

20 3. In a device of the character described, the combination of a driven element, a rotary cam for driving said element, a shaft for driving the cam and having a central bore and diametrically opposite longitudinal slots, a cross pin connected with the cam and extending across the bore and through the slots of the shaft, a rod within the bore attached to the cross pin; means for adjusting the rod longitudinally of the shaft, and means for securing the adjusting means to the shaft.

25 4. In a device of the character described, the combination of a rotary element, a plurality of members connected with the element and equally spaced in a circular row; a cam for successively engaging said members, a shaft for driving the cam and having a central bore and longitudinal slots, pin means connected with the cam and extending into the slots and a rod within the bore attached to the pin means; means for adjusting the rod longitudinally of the shaft, and means for securing the adjusting means to the shaft.

30 5. In a device of the character described, the combination of a rotary element, a plurality of members connected with the element and equally spaced in a circular row; a cam for successively engaging the members, said cam being formed so that the rotary element is turned a certain angular distance in one direction during a portion of one revolution of the cam and held stationary during the remaining portion of said revolution of the cam; a shaft for driving the cam and having a longitudinal bore and longitudinal slots; means connected with the cam and extending across the bore and through the slots of the shaft; a rod within the bore attached to the connecting means; and means for securing the rod to the shaft in a desired position of longitudinal adjustment so that the cam will locate the rotary element in a definite position during the time the rotary element is stationary, and means for securing the adjusting means to the shaft.

35 6. In a device of the character described, the combination of a rotary element, a plurality of members connected with the element and equally spaced in a circular row; a cam for successively engaging the members, said cam being formed so that the rotary element is turned a certain angular distance in one direction during a portion of one revolution of the cam and held stationary during the remaining portion of said revolution of the cam; a shaft for driving the cam and having a longitudinal bore and longitudinal slots; means connected with the cam and extending across the bore and through the slots of the shaft; a rod within the bore attached to the connecting means; and means for securing the rod to the shaft in a desired position of longitudinal adjustment so that the cam will locate the rotary element in a definite position during the time the rotary element is stationary, and means for securing the adjusting means to the shaft.
